(57) **CLAIM**

The ornamental design for a wireless portable power source, as shown and described.

DESCRIPTION

FIG. 1 is a top, front, right side perspective view of a wireless portable power source, shown in a closed position; FIG. 2 is a bottom, rear, right side perspective view thereof; FIG. 3 is a front view thereof;

FIG. 4 is a rear view thereof;

FIG. 5 is a left side view thereof;

FIG. 6 is a right side view thereof;

FIG. 7 is a bottom view thereof; and

FIG. 8 is a top view thereof; and

FIG. 9 is a bottom, rear, right side perspective view of the wireless portable power source, shown open and in a usage state; and,

FIG. 10 is enlarged view of an encircled portion of the wireless portable power source in FIG. 2.

The broken lines in the figures depict portions of the wireless portable power source that form no part of the claimed design.

1 Claim, 10 Drawing Sheets

UNITED STATES PATENT AND TRADEMARK OFFICE
CERTIFICATE OF CORRECTION

PATENT NO. : D1,031,642 S
APPLICATION NO. : 29/785619
DATED : June 18, 2024
INVENTOR(S) : Zhuowen Liao

Page 1 of 3

It is certified that error appears in the above-identified patent and that said Letters Patent is hereby corrected as shown below:

In the Drawings

In FIGS. 4 and 8 features shown in dashed lines and FIGS. 1 and 3 are shown in solid lines.
FIGS. 4 and 8 to be replaced with corrected FIGS. 4 and 8 as shown on the attached drawing sheets.

Signed and Sealed this
Eighteenth Day of March, 2025

Coke Morgan Stewart
Acting Director of the United States Patent and Trademark Office
